UNITED STATES PATENT OFFICE.

NELLIE B. SMITH, OF ENGLEWOOD, COLORADO.

PORTABLE TOILET.

Application filed August 27, 1925. Serial No. 52,875.

To all whom it may concern:

Be it known that I, NELLIE B. SMITH, a citizen of the United States, residing at Englewood, in the county of Arapahoe and 5 State of Colorado, have invented certain new and useful Improvements in Portable Toilets, of which the following is a specification, reference being had to the accompanying drawings.

10 This invention relates to toilets or water closets, and particularly to portable toilets.

The general object of the invention is to provide a device of this character which is very simple, which may be folded up in 15 a small compass and is, therefore, readily carried, and which is particularly adapted to be carried upon a car with other camp equipage and adapted to be set up at any time desired.

20 A further object is to provide a device of this character which has corner posts with canvas walls, the corner posts being made in sections and the canvas walls so formed that they may be readily folded.

25 A still further object is to provide a device of this character with a folding seat and provided with means which will brace the structure when a person is resting upon the seat.

30 Other objects will appear in the course of the following description.

My invention is illustrated in the accompanying drawings, wherein:—

Figure 1 is a perspective view showing 35 my foldable toilet erected;

Figure 2 is a horizontal section through the middle portion of the toilet looking down upon the seat;

Figure 3 is a view of the canvas walls 40 laid out flat preparatory to folding up the sections;

Figure 4 is a view of the toilet folded up;

Figure 5 is a vertical sectional view through the toilet;

45 Figure 6 is an elevation of one of the sectional supports;

Figure 7 is an elevation of one of the cross braces;

Figure 8 is a cross section showing the 50 toilet seat construction.

Referring to these drawings, it will be seen that the toilet structure is square in cross section or rectangular, and that it is formed of canvas walls and uprights at the 55 corners. These uprights, as illustrated in

Figure 6, are formed of three sections 10, 11 and 12, the section 10 being pointed, as at 13, so that it may be driven into the ground and at its upper end being formed with a socket. The section 11 has a pin 14 which 60 engages in said socket and at its upper end has a socket in which a pin 14 on the section 12 engages. The upper end of the section 12 is provided with an upwardly projecting pin 15 for a purpose to be later described.

Preferably the walls of the toilet are formed of canvas, as hereinbefore described, adapted to be folded along the dotted lines in Figure 3 into three sections A, B and C. 70 The section B is the only one which is attached permanently to the posts. This section is attached by suitable attaching members 16 to the middle section 11 of the four posts. The sections A and C, however, are 75 unattached or only temporarily attached. The section A at one end is formed with a flap 17 having slits or openings which may be engaged with fastening means on the other end of the section A, as shown in Figure 1, so as to hold the flap or door closed. The four posts formed of the sections 10, 11 and 12 are held in quadrangular relation by means of the cross braces 18 which are 80 bolted together at their middles or otherwise connected, as at 19, the ends of the braces having holes 20 adapted to receive the pins 15 on the upper ends of the sections 12. After the toilet is erected it may be held against spreading at its upper ends by 90 a cable or rope 21 engaged over these pins, as shown in Figure 1.

Hingedly mounted within the closet and to what may be termed the rear posts is the seat 22, which is preferably formed of a 95 canvas web 23 attached to side supports 24. This frame carries foldable legs 25 hinged to the frame of the seat and adapted to be folded up so that the seat and the frame may be folded up into the position shown in Figure 3 or against the canvas section B. Preferably, and for the purpose of bracing the structure, two guys 26 are provided which may have screw eyes 27 at their inner ends which are engageable through the canvas 100 wall with the framework of the seat, these guys being stretched laterally outward and staked to the ground, as shown in Figure 1. This will hold the seat expanded and give it strength and take care of any lateral 110

strains. Preferably the canvas will be folded over at its margins so as to form a relatively strong hem.

When it is desired to fold up the structure, 5 the canvas is detached from the posts, the several sections of the posts are detached from each other and laid in parallel relation, and the canvas then folded up, as illustrated in Figure 4, the bracing strips 18 and 10 the guys, of course, being placed inside the folded canvas, the whole being held together by straps. The wall section B may also be provided with a pocket 28 for toilet paper. Straps 29 are used to hold the canvas 15 in its folded form.

While I have illustrated certain details of construction and arrangement of parts, it will be understood that these might be varied in many ways without departing from the 20 spirit of the invention as defined in the appended claims. The device is simple, light, very compact, and may be easily set up and taken down. While I have illustrated only the section B as being attached to the 25 sections 11 of the supporting posts, it is obvious that the sections A and C might also be attached to the sections of the supporting posts. The device is particularly convenient for tourists, it is readily carried 30 on the running board of a car and set up in almost any place, and it is also useful as a temporary closet structure or toilet structure such as are used by mechanics where house building or other work is going 35 on.

I claim:

1. A portable closet structure of the character described including a plurality of posts, each post being made in interfitting sections, 40 a wall of canvas adapted to go around all four posts and form an end closure, the middle portion being attached to the middle sections of the posts, means for bracing the upper ends of the posts from each other to 45 thereby keep the canvas stretched taut, and a seat operatively supported upon said posts.

2. A portable closet structure of the character described including a plurality of posts, each post being made in interfitting sections, 50 a wall of canvas adapted to go around all four posts and form an end closure or door, the middle portion of the canvas being permanently attached to the middle sections of the posts, means for bracing 55 the upper ends of the posts from each other to thereby keep the canvas stretched taut, and a seat hingedly mounted upon said posts and foldable in a vertical position against the canvas or into a horizontal position 60 on legs operatively connected to the free edge of the seat.

3. A portable closet structure of the character described including a plurality of posts, these posts being made in interfitting sections, a wall of canvas adapted to go 65 around all four posts and form an end closure, the middle portion of the canvas being attached to the middle sections of all of the posts, means for bracing the upper ends of the posts from each other to thereby 70 keep the canvas stretched taut, a seat hingedly mounted upon said posts and foldable into a vertical position against the canvas or into a horizontal position, legs operatively connected to the free edge of the 75 seat, and guy wires exterior to the structure and having screw eyes adapted to be engaged with the frame of the seat.

4. A structure of the character described comprising four posts, each formed in three 80 sections, the three sections having means whereby they may be engaged with each other, the uppermost section carrying upwardly extending pins at their upper ends, a wall of canvas adapted to be extended 85 around said post and constituting a wall of said structure, the middle portion of said wall being attached to the middle sections of the posts, cross braces having apertures at their ends to receive the pins and the upper 90 ends of said posts, and a flexible element extending around said pins.

5. A structure of the character described including four posts, a wall of canvas adapted to be extended around the posts to enclose the structure, a seat hingedly mounted upon two of the supporting posts and consisting of a web of canvas and two parallel supports, legs hinged to the forward 95 ends of the parallel supports and adapted 100 to rest upon the ground when the seat is in a horizontal position, and guy wires engageable through the canvas wall and with the forward ends of the seat supports extending laterally in opposite directions to 105 thereby prevent sagging of the seat.

6. A closet structure of the character described including a plurality of posts, a canvas wall operatively connected to said posts, the posts being adapted to be disposed in quadrilateral relation, a canvas seat hingedly connected to two of said posts, legs for supporting the forward edge of the canvas seat, and guys extending through the canvas wall and engaging with the forward 110 edge of the seat, thereby holding the seat extended and preventing sagging of the seat under weight.

In testimony whereof I hereunto affix my signature.

NELLIE B. SMITH.
